RENEWABLE KNIFE BLADE AND CARTRIDGE TYPE FUSE

Filed April 10, 1928

UNITED STATES PATENT OFFICE.

FRANK L. YOUNG, OF SAN ANTONIO, TEXAS.

RENEWABLE KNIFE-BLADE AND CARTRIDGE TYPE FUSE.

Application filed April 10, 1928. Serial No. 268,986.

This invention relates to renewable knife blade and cartridge fuses.

An object of the invention is the provision of a fuse having a removable fusible element which may be replaced when necessary and in which the ends of the fusible element are clamped between a movable partition and a closure cap.

A further object of the invention is the provision of a fuse having a movable partition located at each end and a passage through which is adapted to be inserted, the free end of a fusible element with the free end bent in close contact with the outer face of a partition and clamped thereto by a closure, the partition being either pivoted or removably mounted in an end of the fuse and maintained against rotation by oppositely disposed lugs projecting laterally from the periphery of the partition and received within sockets in a brass ferrule mounted upon a body formed of insulating material.

This invention will be best understood from a consideration of the following detailed description, in connection with the accompanying drawings; nevertheless, it is to be understood that the invention is not confined to the disclosure being susceptible of such changes and modifications as shall define no material departure from the salient features of the invention as expressed in the appended claims.

In the drawings:—

Figure 1 is a vertical section showing my invention applied to one form of fuse.

Figure 2 is a horizontal section taken along the line 2—2 of Fig. 1.

Figure 3 is a vertical section of a slightly modified form of the invention shown in Fig. 1,

Figure 4 is a horizontal section taken along the line 4—4 of Fig. 3,

Figure 5 is a vertical section of the form similar to that shown in Fig. 1 applied to the cartridge fuse,

Figure 6 is a vertical section of the form similar to the knife blade fuse shown in Fig. 3,

Figure 7 is a fragmentary vertical section of one end of a cartridge fuse showing a further modified form of the invention,

Figure 8 is a fragmentary vertical section of a further modified form of a knife blade fuse,

Figure 9 is a horizontal section taken along the line 9—9 of Fig. 8,

Figure 10 is a fragmentary vertical section of a further modified form of the knife blade fuse shown in Figs. 1 and 3,

Figure 11 is a horizontal section taken along the line 11—11 of Fig. 10,

Figure 12 is a view in perspective of a fusible element, one form of the fusible element employed in connection with the fuse,

Figure 13 is a modified form of the fusible element shown in Fig. 12.

Referring more particularly to the drawings, 20 designates a hollow body formed of insulating material to which is secured at the opposite ends thereof metal ferrules 21 upon which are threaded caps 22. The outer end 23 of a ferrule forms a seat for a partition 24.

This partition is provided with laterally projecting pintles or lugs 25, which are received within sockets 26 formed in the opposite side walls of the metal ferrule 21. One portion of the partition, as shown at 27, is cut away to provide a passage. The portion of the partition, as shown at 28, and adjacent the cut away portion 27, is reduced in size so that it will move within the ferrule 21. The remaining portion, as shown at 29, is of sufficient area to rest upon the upper edge of the ferrule 21. By this construction and the pivoting of the partition on the pintle 25, the reduced portion of the partition may be moved into the ferrule when it is desired to apply a new fusible element to the fuse. The fusible element 30 has its opposite ends 31 bent at an angle to the body of the element and located through the partition 24, and a closure disk knife blade section 32. When the cap 22 is screwed down upon the ferrule 21, the end 31 of the fusible element 30 will be clamped between the partition and the disk 32.

The disk 32 is formed integrally with a knife blade 33, the blade projects outwardly therefrom, and is adapted to be engaged in the usual manner by a pair of spaced contacts. From the inner face of the partition 32 projects lugs 34 adapted to be received within sockets 35 formed in the ferrule 21, in order to prevent rotation of the disk 32. The outer end of the cap 22 is provided with a flange 36, which engages the outer face of the disk 32 adjacent the periphery thereof for clamping the disk 32 onto the free end 31 of the fusible element 30.

In applying the fusible element 30 to the fuse, the caps 22 are removed and likewise

the disk 32 or knife blade section, the free ends 31 of the fusible element are then inserted through the passages 27 in the partition 24 and bent into flat contact with the outer face of the partition. The disk 32 or knife blade section is then applied and the cap 22 is screwed into position whereby the free ends of the fusible element are clamped rigidly together. The construction shown in Fig. 3 is identical with the construction shown in Figs. 1 and 2 except that where the partition is cut away in Figs. 1 and 2, the partition 24 in Fig. 3 is provided with a slot 40 through which is inserted the fusible element 30. The other elements of the fuse are designated with similar reference numerals found in Figs. 1 and 2.

Referring to the modified form shown in Fig. 5, it will be seen that the body member 45 is formed of non-conducting material and has mounted at the opposite ends and connected thereto, brass ferrules 46. The ferrule has a reduced portion, as shown at 47, which is threaded to receive the internal threads of a cap shaped contact member 48. The internal portion of the ferrule is provided with a shoulder 49 upon which is adapted to be seated a partition 50 pivoted at 51 to the ferrule 46, as shown in Figs. 1 to 4 inclusive.

The partition 50 is provided with a cut out portion 52 through which is inserted an end of the fusible element 53 with the end 54 clamped between the inner face of the cap 48 and the outer face of the partition 50. The portion of the partition 50 adjacent the cut away portion 52 is reduced in area so that said portion may be moved inwardly of the ferrule when the partition is swung upon its pivots 51.

The modified form shown in Fig. 6 is similar in all respects except that it is provided with a slot 60 instead of a cut away portion through which is inserted an end of a fusible element 53.

In the construction shown in Figs. 8 and 9, the partition 65 is removable from the ferrule 66, since it merely has the portion adjacent the periphery resting upon a shoulder 67 of the ferrule. The partition is provided with a slot 68 through which is inserted an end of the fusible element 69. Said end 70 is clamped between the partition 65 and a disk 71 of a knife blade section which in turn is clamped upon the end 70 by means of a flange 72 of an internally threaded cap 73. The disk 71 is provided with a knife blade 74 projecting outwardly therefrom.

The outer end of the ferrule 66 is provided with notches 75 adapted to receive lugs 76 projecting inwardly from a face of the disk 71 to prevent rotation of said disk.

Referring more particularly to Figs. 10 and 11, it will be seen that a further modified form of the invention is disclosed in

which the partition 80 is provided with laterally projecting lugs 81 adapted to be received within slots 82 in the ferrule 83. The partition is cut away at 84 providing a passage for the insertion of the free end 70 of the fusible element 85 which is clamped as shown at 86 between a disk 87 of a knife blade section and the partition 80. The lugs 81 and the sockets 82 provide for a pivotal mounting of the partition 80, while permitting removal of the partition from an end of the body member 88.

In the construction shown in Fig. 7, the lugs 90 are disclosed projecting laterally from the partition 91 which are received within similar sockets formed in the ferrule 92 so that the partition is removable from the ferrule while having pivotal qualities.

Referring to Fig. 12, a fusible element 93 is shown provided with cut out portions 94 for reducing the element at this point.

The fusible element 95 shown in Fig. 13 is provided with a reduced portion 96 which may be readily fused when too great a current is passed through the same.

It should be noted that various methods may be employed for securing the brass ferrules in all of the different devices of the insulating material and the hollow body, since these various forms of securing means may be applied to any of the construction. Similar reference numerals are being employed to indicate all like forms. The brass ferrules may be pressed or screwed internally or externally on the body members and secured against rotation by means of rivets.

Instead of rivets the metal of the ferrule may be cut or punched to form prongs 101 which are forced into the material of the body. In all of the closure elements passages 102 are provided to permit the escape of gas and air when a fuse is burned. Each partition is provided with a notch or a plurality of notches 103 which are adapted to be engaged by a suitable tool whereby one end of the partition may be raised. Furthermore the outer end of the ferrules may be grooved or not in alignment with the notches in the partitions for facilitating the insertion of the tool.

I claim:—

1. A fuse comprising a hollow body formed of insulating material, a metal ferrule secured to an end of the body and provided with a seat at the outer end, a disk pivoted to the ferrule at diametrically opposite points, and normally supported by the seat, said disk provided with a passage, a fusible link having an end inserted through the passage and bent into flat contact with the outer face of the disk, and means removably connected to the ferrule for clamping the bent end of the link to the disk.

2. A fuse comprising a hollow body formed of insulating material, a metal fer-

rule secured to an end of the body and provided with a seat at the outer end, and a pair of oppositely disposed sockets, a disk having laterally projecting lugs received by the sockets and normally supported by the seat for pivotally mounting the disk, said disk provided with a passage, a fusible link having an end inserted through the passage and bent into flat contact with the outer face of the disk, and means removably connected to the ferrule for clamping the bent end of the link to the disk.

3. A fuse comprising a hollow body formed of insulating material, a metal ferrule secured to an end of the body and provided with a seat at the outer end and a pair of oppositely disposed sockets, a disk having laterally projecting lugs received by the sockets and normally supported by the seat for pivotally mounting the disk, said disk provided with a passage, a fusible link having an end inserted through the passage and bent into flat contact with the outer face of the disk, and means removably connected to the ferrule for clamping the bent end of the link to the disk, said disk being movable from the seat.

4. A fuse comprising a hollow body formed of insulating material, a metal ferrule secured to an end of the body and provided with a seat at the outer end, a disk pivoted to the ferrule, and normally supported by the seat, said disk provided with a passage, a fusible link having an end inserted through the passage and bent into flat contact with the outer face of the disk, and means removably connected to the ferrule for clamping the bent end of the link to the disk, said disk being movable to a position where it will align with the longitudinal axis of the body, with a portion of the disk being disposed within the ferrule.

5. A fuse comprising a hollow body formed of insulating material, a metal ferrule secured to an end of the body and provided with a seat at the outer end, a disk pivoted to the ferrule, and normally supported by the seat, said disk provided with a passage, a fusible link having an end inserted through the passage and bent into flat contact with the outer face of the disk, and means removably connected to the ferrule for clamping the bent end of the link to the disk, said disk being movable to a position where it will align with the longitudinal axis of the body, with a portion of the disk being disposed within the ferrule.

5. A fuse comprising a hollow body formed of insulating material, a metal ferrule secured to an end of the body and provided with a seat at the outer end, a disk pivoted to the ferrule, and normally supported by the seat, said disk provided with a passage, a fusible link having an end inserted through the passage and bent into flat contact with the outer face of the disk, means removably connected to the ferrule for clamping the bent end of the link to the disk, said disk being movable to a position where it will align with the longitudinal axis of the body, with a portion of the disk being disposed within the ferrule, the portion of the disk which is adapted to be moved into the ferrule having the periphery cut away on the arc of a curve, the radius of the curve being less than the radius of the periphery of the remaining portion of the disk.

FRANK L. YOUNG.
